UNITED STATES PATENT OFFICE.

OLIVER L. SCOTT, OF SAN FRANCISCO, CALIFORNIA.

THEFT-ALARM FOR AUTOMOBILES.

1,327,573.

Specification of Letters Patent.

Patented Jan. 6, 1920.

Application filed December 27, 1917. Serial No. 209,065.

To all whom it may concern:

Be it known that I, OLIVER L. SCOTT, a citizen of the United States, residing at the city and county of San Francisco and State 5 of California, have invented new and useful Improvements in Theft-Alarms for Automobiles, of which the following is a specification.

This invention relates to a theft alarm for

10 automobiles.

One of the objects of the present invention is to provide a simple, compact, cheaply manufactured theft alarm mechanism for automobiles which may be easily applied to 15 practically any make of car and which is capable of producing an audible alarm the moment a thief or other unauthorized person attempts to get away with the car, whether it be towed or driven under its own 20 power.

Another object of the invention is to provide means for operating the alarm in connection with the clutch pedal of the car or any other member which must necessarily be 25 operated if the car is moved; and also to provide means for continuously sounding the alarm once it has been started.

Another object of the invention is to provide means for limiting the movement of 30 the clutch pedal to such an extent that it will be impossible to free or release the clutch and also to provide means for marking any unauthorized person that may enter the car and also to provide a sand box, 35 the outlet to which is automatically opened to leave a trail of sand behind the car if it is moved. Further objects will hereinafter appear.

The invention consists of the parts and 40 the construction and combination of parts as hereinafter more fully described and claimed, having reference to the accompanying drawings, in which—

Figure 1 is a side elevation of an automobile, partly in section, showing the application 45 of the invention.

Fig. 2 is a detail view of one part of the mechanism.

Fig. 3 is a detail view of the sand valve.

50 Fig. 4 is an enlarged view of the audible sounder.

Fig. 5 is a detail sectional view of the working device.

Referring to the drawings in detail, A 55 indicates in general a standard form of automobile, 2 the clutch pedal on the car, and

3 the floor. Suitably secured under the car is an air tank 4 which may be charged by a hand pump, a compressor, or any other suitable means, and positioned directly ahead of 60 said tank is a police whistle, which is operated by the air from the tank, a valve 6 being interposed to regulate the volume of air used and to open and close the supply of air.

65 Mounted directly ahead of the whistle is a sand box 7. Mounted in the bottom of said box is a standard form of valve 8 which is adapted to be opened and closed in unison with the valve 6 by means of a lever 9. The 70 valve 6 is also provided with a lever, as shown at 10, and both levers are in this instance connected to a flexible rod or wire 11, which in turn is connected with a hook-shaped latch 12. This latch is inclosed by a 75 casing member 13 secured directly below the foot-board 14 in the car. The casing is also provided with a key-actuated lock 15 which is positioned in direct alinement with the latch 12. The bolt of the lock is adapted to 80 be turned by means of a key 16 and it has formed on its inner end a cam member 17 which is adapted to be turned into or out of engagement with the latch 12; the latch 12 being under normal conditions held in the 85 raised position shown in Fig. 2 by means of a spring 18. This spring is depressed the moment the bolt is turned by means of the key 16 to turn the cam 17 into engagement with the latch, and it will also be seen, by 90 referring to Fig. 2, that the outer end of the latch when depressed, which is hook-shaped as shown at 19, assumes a position in direct alinement with a pin 20 formed on the clutch pedal 2.

95 The owner of a car, when employing a theft alarm of the character described, only inserts the key and turns it so that the cam 17 will depress the latch into alinement with the pin 20 on the pedal. He then removes the key and can safely leave the car as a thief or any other unauthorized person in trying to move the car is sure to set off the alarm and thereby attract sufficient attention to prevent a get-away.

100 The depressing of the clutch pedal to throw out the clutch would, of course, cause the pin 20 to engage the hook 19 and pull it in a forward direction as it is directly connected with the latch and the valves 6 and 8 would then open and permit the air to enter the police whistle, causing this to 110

sound, and then permit sand to escape from the box 7 and leave a trail by which the car could be traced, if the thief should still attempt to get away with the car. The releasing of the clutch pedal would in the present instance be of no avail as the alarm after once being started will continue until the tank 4 has been completely exhausted. This is accomplished by forming a notch 21 on the inner end of the latch 12. This notch moves into register with the cam 17 when the pedal 2 is depressed and here automatically locks itself, thus preventing the latch and the rod 11 from returning even though the pedal 2 should be released. Sand will, therefore, continue discharging from the valve 8 and air will continue to escape through valve 6 to operate the whistle, thus maintaining a noise which is bound to attract the attention of individuals in the vicinity. A thief or other person trying to remove the car is in this manner apprehended and often caught and prevented from stealing the car.

25 While the tank 4 and the sand box are shown as positioned below the floor line of the car, it is obvious that they may be placed under the seat or at any other convenient point, and that while the latch 12 is shown 30 as operated by the clutch pedal 2 it is also obvious that it may be operated by any other member which must necessarily be moved if the car is towed or driven away by its own power.

35 The alarm after once being started will continue operating until the tank 4 has been exhausted and the sand box will also continue discharging its contents until emptied. If the owner should be notified, it is obvious 40 that it is only necessary for him to insert the key 16 and turn the bolt until the cam moves out of register with the notch 21. The latch would then be automatically released and return to normal position, this 45 being accomplished by attaching a spring 25 to one of the levers, as shown in Fig. 4. It is therefore not necessary to completely exhaust either the tank or the box after the alarm has been started if the thief is at 50 once apprehended.

The alarm mechanism is thrown into and out of action at all times at the will of the operator. If he is driving the car it is natural that the alarm mechanism remains 55 in an inoperative position and that when the operator leaves the car it is thrown into operative position by means of the key.

By referring to Fig. 2 it will be seen that the latch 12 is provided with a collar 12^a. 60 This collar although it permits the clutch to move a certain distance forward serves as a stop to prevent the clutch pedal from completely releasing the clutch. The movement of the pedal and the position of the collar 65 12^a are, however, sufficient to permit the

latch to move forward sufficiently far to operate the different valves and the alarms actuated thereby. The stop collar 12^a positively locks the pedal against entirely freeing the clutch, thus rendering it difficult, if 70 not impossible, for any one attempting to drive the car away to change gears or, in fact, get the car under headway.

The car is also equipped with a marking device. This consists of a tube 30 (see Fig. 75 5), the upper end of which is adapted to be filled with flour or other material. The flour is placed in the upper end of the tube and an S trap 31 formed on the tube prevents it from dropping or settling below this 80 level. The main vertical section of the tube is provided with two perforated disks 32 between which is mounted a cork 33. This cork normally seats on the lower disk but is raised by air against the upper disk when 85 the valve 34 is opened. The handle of this valve is, of course, moved in unison with the handle 10 of the whistle valve and it can therefore be seen that releasing or depressing of the clutch pedal not only starts the 90 police whistle and opens the sand box, but it also causes a sufficient amount of air to pass through the tube 30 to blow the flour out and directly against the back of any one who may be seen in the car, thus marking 95 any individual that may attempt to get away with the car so that if he tries to escape he may be traced by the flour mark deposited on the back of his clothing. The cork 33 interposed between the perforated 100 disks rises against the upper perforated disk the moment the valve 34 is opened. The volume of air displaced by the cork during its upward movement is sufficient to blow out the flour contained in the upper 105 end of the tube and as the cork seats against the upper perforated disk, it can readily be seen that it will form a seal at this point to prevent the further escape of air. This is of importance as it permits the whistle to 110 operate a greater period of time than would be possible if the air should continue to escape through the tube 30.

The mechanism, including the air tank, the sand box and the key-actuated latch together with the valves and means for operating same, may all be inclosed by a pan such as shown at 40, if desired, thus rendering it impossible for any one to tamper with the mechanism or render it inoperative. 115 120

Having thus described my invention, what I claim and desire to secure by Letters Patent is—

1. A theft alarm for automobiles, comprising a pivotally mounted latch having a 125 hook formed on one end, a pin formed on the clutch pedal of the car, a key-actuated member for raising or lowering the hook-shaped end of the latch into or out of engagement with the pin, a source of air sup- 130

- ply, a whistle connected with said source of air supply adapted to be operated thereby, a valve interposed between the air supply and the whistle, and means connected 5 with the latch for opening the valve and for maintaining it open when the clutch pedal is depressed.
2. A theft alarm for automobiles, comprising a pivotally mounted latch having a 10 hook formed on one end, a pin formed on the clutch pedal of the car, a key-actuated member for raising or lowering the hook-shaped end of the latch into or out of engagement with the pin, a source of air supply, a whistle connected with said source of air supply adapted to be operated thereby, a valve interposed between the air supply 15 and the whistle, means connected with the latch for opening the valve and for maintaining it open when the clutch pedal is depressed, and a key-actuated member for maintaining the latch either in a depressed operative position or in a raised inoperative position.
- 25 3. The combination with a clutch pedal on an automobile, of an audible sounder, a key-actuated member permitting a predetermined movement of the clutch pedal but preventing disengagement of the clutch, 30 means actuated by the limited movement of the clutch pedal for operating the sounder, means also actuated by the clutch pedal movement for projecting a predetermined quantity of flour and means for 35 continuously operating the sounder once it has been started.
4. The combination with the clutch pedal on an automobile of a whistle, means for supplying said whistle with air to operate 40 the same, a valve interposed between the source of air and the whistle, means connected with the clutch pedal for opening
- said valve, means for retaining the valve open after it has been opened, a container for flour, means for passing a portion of the air from the source of supply through 45 said container to eject it against the back of any one occupying the driver's seat in the automobile.
5. The combination with the clutch pedal 50 on an automobile of a sounder, means for supplying said sounder with air to operate the same, a valve interposed between the source of air and the sounder, means connected with the clutch pedal for opening said valve, means for retaining the valve open after it has been opened, and means for limiting the movement of the clutch pedal 55 so that the clutch operated thereby cannot be released.
6. The combination with the clutch pedal 60 on an automobile of a whistle, means for supplying said whistle with air to operate the same, a valve interposed between the source of air and the whistle, means connected with the clutch pedal for opening said valve, means for retaining the valve open after it has been opened, a container for flour, means for passing a portion of the air from the source of supply through 65 said container to eject it against the back of any one occupying the driver's seat in the automobile, a sand box carried by the car and means connected with the clutch pedal for opening a discharge passage formed in the 70 sand box.
- In testimony whereof I have hereunto set my hand in the presence of two subscribing witnesses.
